DESIGN FOR AN IRONING BOARD ATTACHMENT

Thelma V. Baker, Fort Wayne, Ind.

Application May 19, 1943, Serial No. 110,235

Term of patent 14 years

To all whom it may concern:

Be it known that I, Thelma V. Baker, a citizen of the United States, residing at Fort Wayne, in the county of Allen and State of Indiana, have invented a new, original, and ornamental Design for an Ironing Board Attachment, of which the following is a specification, reference being had to the accompanying drawing, forming part thereof.

I claim:

The ornamental design for an ironing board attachment, as shown.

THELMA V. BAKER.
